COMBINATION TOOTHBRUSH, WATER
GLASS, AND SOAP HOLDER

Frank J. Bidmon, Rockford, Ill.

Application September 26, 1946, Serial No. 699,381

4 Claims. (Cl. 312—206)

1

This invention relates to a combined toothbrush, water glass and soap holder for household use, and is especially concerned with such a holder in which several toothbrushes may be separately accommodated in individual sanitary compartments for protection against dust and other contamination.

One object of the invention is to provide a unitary holder for a toothbrush, water glass and soap holder which will automatically eject a selected toothbrush where it can be easily grasped by the user.

Another object is the provision of such a unitary device which may be easily and quickly mounted or demounted from its support for cleaning.

Other objects and advantages will become apparent from the following description in connection with the drawings, in which—

Figure 1 is a perspective view of one modification of the present invention;

Fig. 2 is an end view of Figure 1 as seen from the left;

Fig. 3 is a longitudinal sectional view of the device taken along the line 3—3 of Fig. 2 showing one of the toothbrush holder compartments;

Fig. 4 is a partial back view showing one of the supporting slots, and

Fig. 5 is a fragmentary sectional view of Fig. 2 taken along the line 5—5.

A preferred form of my invention is illustrated in the drawings in which 1 indicates generally a body composed of aluminum or other metal, porcelain, glass, plastic or any other suitable material. In its top surface or wall are provided a round recess 2 for a water glass and a rectangular recess 3 having ribs 4 for supporting a bar of soap. An upstanding apron 6 is provided at the back to serve as a splash shield for the wall or other support on which the device is mounted.

The body is formed with three horizontally extending separate compartments 7, defined by upstanding wall portions interconnecting the top and bottom walls, each for an individual toothbrush 8. While three toothbrush compartments have been shown in the present instance, obviously any number of compartments from one upward may be employed as preferred. At one end of each compartment is an opening 9 formed with a frusto-conical seat 11 frictionally engageable with a similarly formed surface 12 on a closure plug 13. Each plug has a knurled outer surface 14 to facilitate handling and is attached to the body by a chain 16 to prevent misplacement. Plugs may be made of metal or any other material

suitable; it will generally be preferable to make them of some material which lends itself to individual distinctive colors for the different plugs so as to readily identify the compartment for a particular toothbrush. A series of apertures 17 is provided in each compartment wall to permit the toothbrush to dry and maintain it in a dry sanitary condition. Each compartment has means for urging the toothbrush 8 against the plug 13 so that when the latter is removed the toothbrush will be ejected sufficiently that it may be readily grasped by the user. This urging means in the present instance is shown as a pin 18 reciprocably fitted in a bore 19. Each pin has an inner and outer abutment or shoulder 21 and 22 for engaging one side or the other of the compartment end wall 23 to limit movement of the pin in both directions. The shoulder 22 may also form a handle by which the position of the shoulder 21 may be controlled from the exterior of the compartment. To facilitate assembly the shoulder 21 will be threadedly attached to the inner end of the pin 18 as shown. A helical coil spring 24 preferably of some rustless material such as stainless steel or brass is compressibly interposed between the inner shoulder 21 and the inner surface 26 of the compartment end wall 23 so as to urge the inner shoulder inward against one end of the toothbrush to urge the opposite end against the closure plug 13 when the latter is seated on surface 11.

In use, a toothbrush may be selected by removing a particular one of the plugs 13 which, as above mentioned, may be identified by a particular color. As the plug is removed the end of the toothbrush will be moved out of the compartment by spring 24, the movement of which is limited by engagement of the shoulder 22 with the body wall 23. After the toothbrush has been used it will be replaced simply by inserting it in the compartment through the opening 9 and pressing it against the shoulder 21 to compress spring 24 by forcing the plug 13 into frictional engagement with the frusto-conical body surface 11.

To facilitate cleaning, it is preferable that the body be readily removable and replaceable. A pair of spaced slots 27 will be formed in the bottom edge of the back wall 28. Each slot will be downwardly and inwardly enlarging, as shown in Figs. 4 and 5, and will be engageable with a similarly formed lug 29 on bracket 31 mounted to the wall or support 32 by screws 33. Thus, removal of the holder 1 for cleaning may be readily accom-

plished simply by lifting it to disengage slots from bracket lugs 29.

It will now be clear that the holder of my invention is well adapted for keeping the brushes dry, clean, and sterile, practically regardless of the air conditions surrounding the holder. Thus, since each of the compartments is completely enclosed, no dust, foreign matter, or liquid may be deposited on the brushes, and contact between the individual brushes is prevented. Furthermore, a structure is provided in which the water glass, soap, and any particular toothbrush are all equally readily available.

While a particular form of the present invention has been shown it will be apparent that minor changes therein will readily suggest themselves to others skilled in the art without departing from the spirit and scope of the invention. Having thus described the invention, what is claimed as new is:

1. A bathroom fixture for attachment to a wall or the like, comprising a one-piece body defined by spaced upper and lower walls, said upper wall having upstanding ribs thereon to define spaced upwardly facing recesses, one of circular and one of rectangular configuration, said upper and lower walls being interconnected by spaced upstanding walls to define a horizontally extending passageway shaped to receive a toothbrush, said passageway at one end opening on to an end of the body, a removable closure for said opening and resiliently mounted abutment means mounted at the opposite end of the passageway, said means being movable between a first position in which the abutment is forced toward the extreme opposite end of the passageway by insertion of the brush in the passageway through said opening and with the removable closure in position to close the opening and a second position in which the abutment is urged toward the opening to partially eject the toothbrush from the passageway when the closure is removed to uncover said opening.

2. The combination recited in claim 1 with means connected to the abutment means projecting through the opposite end of the body to be engageable with the body to limit movement of the abutment means and to define a handle by which the abutment means is manually movable from its ejecting position to its retracted position to facilitate insertion of the toothbrush in the compartment and the closure in the opening.

3. A bathroom fixture, comprising in combination a body defined by spaced elongated horizontally extending upper and lower walls, said upper walls having upstanding ribs thereon positioned to define spaced upwardly facing recesses, one of circular and one of rectangular configuration, spaced upstanding wall portions interconnecting said upper and lower walls to define at least one substantially enclosed horizontally extending compartment in said body shaped to receive an

individual toothbrush, said compartment having an opening at one end of the body, a plug insertable in said opening from the exterior of the body for closing said compartment, resiliently mounted abutment means within said compartment movable to a retracted position upon insertion of the brush in the compartment arranged to urge the toothbrush outwardly through said opening when the plug is removed, said bottom wall having apertures providing communication between said compartment and the atmosphere to effect circulation of air about the enclosed toothbrush, means formed on said body for mounting it on a support attached to a wall and an upstanding apron at one side of said body integral with said upper wall and forming a splash shield to protect the wall adjacent the body.

4. A bathroom fixture comprising a body defined by spaced upper and lower walls, spaced end walls interconnecting said upper and lower walls at opposite ends of the body, spaced upstanding walls interconnecting said upper and lower walls and end walls to define at least one horizontally extending compartment for receiving an individual toothbrush, one of said end walls having an opening having an outwardly flaring frusto-conical seat, a plug with a frusto-conical surface shaped to be frictionally engageable with said seat to provide a closure for said opening, the other end wall having a bore in communication with the compartment, a pin extending through said bore movable between preselected positions having a first abutment disposed in said compartment and a second abutment on the exterior of said body, in one position of said pin, said second abutment being engageable with said other end wall and said first abutment being spaced inwardly of the compartment from said other end wall to partially eject the toothbrush and in the other position of the pin said first abutment being disposed against said other end wall by the toothbrush being inserted in the compartment and the second abutment being spaced outwardly from said other end wall, and spring means acting between the body and the first abutment to normally urge said pin to the first described position.
